(57) **CLAIM**

I claim the ornamental design for an electric fat tire bike, as shown and described.

DESCRIPTION

FIG. 1 is a front and right side perspective view of an electric fat tire bike embodying my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the drawings depict portions of the electric fat tire bike that form no part of the claimed design.
